(57) **CLAIM**

I claim the ornamental design for a tent, as shown and described.

DESCRIPTION

FIG. 1 is a front perspective view showing my new design;
FIG. 2 is a rear perspective view thereof;
FIG. 3 is a left side perspective view thereof;
FIG. 4 is a right side perspective view thereof;
FIG. 5 is a top perspective view thereof;
FIG. 6 is an alternative front perspective view thereof;
FIG. 7 is an enlarged view of detail area 7-7 of FIG. 5;
FIG. 8 is an enlarged view of detail area 8-8 of FIG. 5;
FIG. 9 is an enlarged view of detail area 9-9 of FIG. 5;
FIG. 10 is an enlarged view of detail area 10-10 of FIG. 5;
FIG. 11 is an enlarged view of detail area 11-11 of FIG. 3; and,
FIG. 12 is an enlarged view of detail area 12-12 of FIG. 4. The dashed lines depict portions of the tent in which the design is embodied that are not considered part of the claimed design.
